(57) **CLAIM**

The ornamental design for an actuator for two-way valves,
as shown and described.

DESCRIPTION

FIG. 1 is a front elevational view of the actuator for two-way valves showing my new design;

FIG. 2 is a rear elevational view thereof;

FIG. 3 is a top plan view thereof;

FIG. 4 is a bottom plan view thereof;

FIG. 5 is a right side view thereof;

FIG. 6 is a left side view thereof;

FIG. 7 is a cross-sectional view thereof taken along the line
7-7' in FIG. 5; and,

FIG. 8 is a perspective view thereof.

The broken lines shown in the figures are for the purpose of
illustrating portions of the actuator for two-way valves and
form no part of the claimed design.
